UNITED STATES PATENT OFFICE.

ROBERT E. EINSTEIN, OF ST. LOUIS, MISSOURI, ASSIGNOR TO AMERICAN FLANGE FROG AND RAILWAY IMPROVEMENT COMPANY, OF ST. LOUIS, MISSOURI, A CORPORATION OF FLORIDA.

FLANGE FROG.

Application filed February 5, 1923. Serial No. 616,991.

To all whom it may concern:

Be it known that I, ROBERT E. EINSTEIN, a citizen of the United States, residing at St. Louis, Missouri, have invented a certain new and useful Improvement in Flange Frogs, of which the following is a full, clear, and exact description, such as will enable others skilled in the art to which it appertains to make and use the same.

10 This invention relates to railway frogs of the type that are known commercially as "flange frogs", and particularly to flange frogs of the kind that are composed of a center cast member provided with an integral frog point, and guard members arranged at opposite sides of said center member and each provided with a portion that extends above the top face of the adjacent running surface of the frog, so as to cause 15 the flange of a passing wheel to be guided properly past the point of the frog by means of a tread rim contact in a horizontal plane above the running surfaces of the frog.

In my prior U. S. Patent No. 1,339,597, dated May 11, 1920, I have illustrated a three-piece flange frog of the general type above referred to, in which the center member is provided with a frog point and also with integral portions that constitute running surfaces on which the treads of the passing wheels travel, said wheel tread portions being separated from each other at the toe of the frog by a groove or wheel flangeway in the center member which 30 branches into two wheel flangeways that extend along the sides of the point of the frog. The center member is provided with integral, laterally-projecting tie engaging portions that support the guard members, and 35 the guard members are constructed in such a way that they can be reversed so as to compensate for wear on the wheel rim engaging portions of said guard members. While a frog of the construction above described 40 can be adjusted to compensate for wear on the portions of the frog that are used to guide a wheel past the point of the frog, no adjustment is provided to compensate for wear on the portions of the frog against 45 which the flanges of the wheels bear. Consequently, if the inner edges or side faces of the wheel tread portions of the center member become excessively worn, it is necessary to remove said center member and re-

place it by a new or perfect center member, 55 because excessive wear on these portions of the center member destroy the gauge of the track.

The main object of my present invention is to provide a three-piece frog which 60 is so constructed that it can be adjusted easily to compensate for wear on the inner edges or side face of the wheel tread portions of the frog, and also to compensate for wear on the wheel rim engaging portions of the frog, thereby prolonging the 65 life of the frog and enabling it to be used for a long period at a point in the track where the traffic on one side of the frog is excessive.

Another object is to provide a three-piece frog in which the guard members are combined with the center member in such a manner that the guard members can be adjusted to compensate for wear without the 70 necessity of completely disconnecting said guard members from the center member and reversing said guard members.

Another object is to provide a cast metal frog that has sufficient inherent resiliency 75 to partially absorb the shock to which the frog is subjected when a wheel passes over the frog.

And still another object is to provide an exceptionally strong and rigid frog of the 80 character above described that is inexpensive to manufacture, easy to adjust and easy to assemble or disassemble.

To this end I have devised a flange frog that is composed of a center member provided on its top side with an upwardly-projecting portion that constitutes the point of the frog, and guard members arranged at opposite sides of said center member and provided with wheel tread portions that constitute the running surfaces of the frog and wheel rim engaging portions that are adapted to be engaged by the outer edge of the rim of a passing wheel in such a way that the flange of the wheel will be guided 90 properly past the point of the frog. Preferably the guard members are combined with the center member in such a manner that they can be adjusted laterally towards and away from said center member to compensate for wear on the wheel rim engaging 95 portions of said guard members and also to compensate for wear on the portions 100 105

2
of said guard members against which the flanges of the wheels bear. In the form of my invention herein illustrated the guard members are so designed that they lap over the center member and said guard members are provided with tie engaging portions that are adapted to be secured to the ties. I wish it to be understood, however, that my broad idea is not limited to a frog 10 of the particular construction herein illustrated, as the particular shape of the various members of the frog is immaterial and said members can be combined in various ways without departing from the spirit of 15 my invention.

Figure 1 is a top plan view of my improved flange frog.

Figures 2, 3, 4, 5, 6, and 7 are cross-sectional views, taken on the lines 2-2, 3-3, 20 4-4, 5-5, 6-6 and 7-7, respectively, of Figure 1.

Referring to the drawings which illustrate the preferred form of my invention, A designates the center member of the frog and B designates the guard members that are arranged at opposite sides of said center member, said members preferably consisting of castings constructed of manganese steel or some suitable steel alloy. The center member A is provided on its top side with an upwardly-projecting, tapered portion 1 that constitutes the point of the frog and the guard members B are so designed that they lap over said center member, as 25 shown in Figures 2, 3 and 4. Each of said guard members is provided with a wheel tread portion 2 and with a wheel rim engaging portion 3 arranged in a higher horizontal plane than the top face of said wheel 30 tread portion. The top faces of the wheel tread portions 2 of the guard members constitute the running surfaces of the frog, and the inner sides or edges 2^a of said portions 2 are spaced apart, so as to form a wheel 35 flangeway 9 at the toe of the frog, as shown in Figure 2, which branches laterally into two wheel flangeways that extend along the sides of the frog point 1, as shown in Figures 3 and 4.

When a wheel passes over the frog the tread of the wheel will travel on the top face of the wheel tread portion 2 of one of the guard members B and the outer edge of the rim of the wheel will bear against 50 the wheel rim engaging portion 3 of said member in such a way that the flange of the wheel will be guided properly past the end of the frog point 1. In order that the frog may be adjusted easily to compensate for 55 wear on the inner edges of the wheel tread portions 2 and also on the wheel rim engaging portions 3, the guard members B are combined with the center member A in such a way that said guard members can be adjusted laterally towards and away from

said center member, thereby making it possible to maintain the proper gauge and also maintain the proper relation between the frog point and the wheel rim engaging portions of the frog, even when the traffic on 70 one side of the frog is excessive. In the form of my invention herein illustrated the lateral adjustment of the guard members is effected by inserting or removing shims, washers or other variable spacing devices 75 between the side faces of the center member A and the portions of the guard members B that are disposed oppositely to the side faces of said center member. When the wheel rim engaging portion 3 and the wheel 80 tread portion 2 of one of the guard members B becomes worn to such an extent that the track is out of gauge or the flange of a passing wheel is liable not to be guided properly past the point of the frog, the 85 spacing devices 4 between said guard member and the center member A of the frog can be adjusted in such a way as to bring said guard member closer to the center member, thereby compensating for wear on both 90 of said portions 2 and 3 by a simple adjustment of only one of the members of the frog. In addition to the desirable feature above pointed out, a frog equipped with 95 spacing devices arranged between the center member and the guard members is inexpensive to manufacture, because it is not necessary to accurately machine the side faces of the center member and the adjacent side faces of the guard members, due, 100 of course, to the fact that the spacing devices 4 prevent said faces from touching or bearing upon each other. Any suitable means can be used for connecting the center member A with the guard members B, 105 but I prefer to clamp the said members together by horizontally-disposed bolts 5 that pass transversely through said parts and provide the guard members with laterally-projecting tie engaging portions 6 that are 110 connected to the track ties by spikes or other suitable fastening devices. If desired, the guard members can be provided with braces 7, so as to reinforce and strengthen the tie 115 engaging portions 6 of said members. The center member is provided at its outer end with a reduced portion 8 to which the track rails are adapted to be connected, as shown in broken lines in Figure 7, and each of the guard members is so constructed at its 120 outer end that a track rail can be connected to same, as shown in Figure 6. While the principal object of forming the running 125 surfaces or wheel tread portions of the frog integral with the guard members B and combining said guard members with the center member in such a way that they can be adjusted laterally, is to enable the frog to be adjusted to compensate for wear, another advantage that results from such a construc- 130

tion is that the frog has a certain amount of inherent resiliency that partially absorbs the shock to which the frog is subjected when a wheel passes over the same. This is not true of a frog cast in one-piece or a frog provided with a center member equipped with integral running surfaces and a frog point, for in such structures it is impossible for the frog point and running surfaces to "give" or move slightly relatively to each other, as in the case of a frog of the articulated type. My improved frog embodies the desirable characteristics of an articulated frog, and it also embodies the desirable features of a cast frog without having the rigidity of a cast frog. Moreover, it is inexpensive to manufacture, it is easy to repair, and as it can be adjusted to compensate for wear on the wheel rim engaging portions and also on the portions that determine the gauge of the track, it can be used for a long period at a point in the track where the traffic on one side of the frog is excessive.

Having thus described my invention, what I claim as new and desire to secure by Letters Patent is:

1. A flange frog, comprising a center cast member provided on its top side with an integral portion that constitutes a frog point, and cast guard members adjustably connected to said center member, each of said guard members having a wheel tread portion whose inner edge is separated from said frog point by a wheel flangeway and a wheel rim engaging portion arranged in a higher horizontal plane than said wheel tread portion.

2. A flange frog, comprising a frog point, and guard members arranged at opposite sides of said frog point and each provided with a wheel tread portion that is separated from said point by a wheel flangeway and a wheel rim engaging portion integrally connected to said wheel tread portion.

3. A flange frog, comprising a frog point, members arranged at opposite sides of said point and each provided with a wheel rim engaging portion and also a wheel tread portion that is separated from the point by a wheel flangeway, and means for enabling the wheel tread portions and the wheel rim engaging portions to be adjusted relatively to the point of the frog to compensate for wear.

4. A flange frog, comprising a frog point, and guard members adapted to be adjusted laterally towards and away from said point, each of said guard members having a wheel tread portion whose inner edge is spaced away from one side of said point and a wheel rim engaging portion arranged in a higher horizontal plane than said wheel tread portion.

5. A flange frog provided with adjustable

wheel rim engaging portions, and an adjustable wheel flangeway.

6. A flange frog, comprising a frog point, and laterally-adjustable members arranged at opposite sides of said point and each provided with a wheel rim engaging portion and a portion that forms one side of the wheel flangeway of the frog.

7. A flange frog, comprising a center member provided with a frog point, guard members arranged at opposite sides of said center member and each provided with a wheel rim engaging portion and a wheel tread portion, and removable spacing devices interposed between said center member and said guard members, for the purpose described.

8. A flange frog, comprising a cast center member provided with a frog point, cast metal guard members arranged at opposite sides of said center member and each provided with a wheel tread portion and a wheel rim engaging portion, the wheel tread portions of said guard members being spaced away from said point so as to form wheel flangeways, and means for connecting said members together.

9. A flange frog, comprising a cast center member provided with a frog point, cast metal guard members arranged at opposite sides of said center member and each provided with a wheel tread portion whose inner edge is separated from said point by a wheel flangeway and whose outer edge merges into a wheel rim engaging portion, means for connecting said members together, and means whereby said guard members can be adjusted laterally towards and away from said center member.

10. A flange frog, comprising a center cast member provided on its top side with a frog point, cast metal guard members arranged in overlapping relation with said center member and each provided with a wheel tread portion whose inner edge is separated from said point by a wheel flangeway and whose outer edge merges into a wheel rim engaging portion, and means for clamping said members together.

11. A flange frog, comprising a center cast member provided with a frog point, cast metal guard members arranged at opposite sides of said center member and each provided with a wheel tread portion and a wheel rim engaging portion, the inner edges of the wheel tread portions of said guard members being spaced away from said frog point so as to form wheel flangeways, integral tie engaging portions on said guard members, and means for clamping said center member and guard members together.

12. A flange frog, comprising a center cast member provided on its top side with a frog point, cast metal guard members arranged at opposite sides of said center mem-

ber in overlapping relation with same and each provided with a wheel tread portion and a wheel rim engaging portion, the inner edges of said wheel tread portions co-operating with said point to form wheel flangeways, laterally-projecting tie engaging portions on said guard members, fastening de-

vices passing transversely through said guard members and center member, and spacing devices interposed between said center member and said guard members, for the purpose described. 10
